UNITED STATES PATENT OFFICE.

WILLIAM SUTTON, OF ST. LOUIS, MISSOURI.

SPRING-BEARING CAR-TRUCK.

SPECIFICATION forming part of Letters Patent No. 531,574, dated December 25, 1894.

Application filed January 13, 1894. Serial No. 496,720. (No model.)

To all whom it may concern:

Be it known that I, WILLIAM SUTTON, of the city of St. Louis, in the State of Missouri, have invented a certain new and useful Improvement 5 in Anti-Concussion Lateral Spring-Bearing Car-Trucks, of which the following is a full, clear, and exact description, reference being had to the accompanying drawings, forming part of this specification.

10 This invention relates to a device for overcoming or largely reducing the concussion of cars, and carriages incident to the passage of the wheels over rough or uneven tracks, or obstructions thereon, which vertical movement, and consequent concussion is thus reduced by means of supplemental laterally projected bearings to those of the axles, which in combination with a bell-crank lever that connects said laterally projected bearings 15 20 with the truck frame above and a coupling beam and tube tension coupling that connect the forward and rear running gear, largely transfers the now injurious vertical concussion of the running gears, into an innocuous lateral spring vibration; and the invention 25 consists in features of novelty hereinafter fully described and pointed out in the claims.

Figure I is a top view of the running gears of a motor or other railway truck, with my 30 anti-concussion spring bearing attachment. Fig. II is an end view of the same, and Fig. III is a side view of the same part in detail section and shows the tubular tie tension jointed main coupling beam of the running 35 gears, and their lateral supplemental spring bearings, connected by the bell-crank levers with the surmounting truck.

Referring to the drawings:—1 represents the rail track. 2 are the car truck wheels, 40 that run thereon. 3 are the axles on which said wheels are fast mounted and which axles have their bearings in the brasses within the pedestals of the spring bearer boxes 4, in which the vertical springs 5 are housed and 45 play.

6 represents the tubular bases of the compound pedestal angle frames 7, which compound or double pedestal frames are cast integral and carry the spring bearer boxes 4. 50 The upper corners of said compound pedestal frames have projecting circular bosses 8 cast thereon, to strengthen them at the points

most subject to fracture, and through those of said bosses located at the inner corners of said compound pedestal frames, and through 55 said frames are bolt holes 9, which correspond with the journal bearer holes, which in consequence are alike numbered 9 through the elbows 10 of each of the four bell-crank levers 11, and through the inner bosses 8', inside said inner upper corners of the compound pedestal frames, which inner bosses serve for side bearings to the elbows of said bell-crank levers. 60 8² are the lugs that project inwardly from the outer upper corners of said compound pedestal frames, and which lugs serve as vertical guides to the bell-crank levers as they vibrate vertically on the spring cushions 16, and during the transposition in a measure of the obnoxious vertical concussion into the innocuous horizontal vibration, that is aided by the influence of the horizontal springs 33 and 35 on the pendent arms of the bell-crank levers. 12 are the journal bolts that occupy their perforate bearer seats 9, and constitute the 70 journals on which said bell-crank levers work, and which journal bearings of said bell-crank levers are each respectively about one quarter way concentrically removed toward the midway point between the forward and rear axle 75 80 bearings, and thus to a relative extent is reduced the obnoxious concussion from the respective rise and fall of the surmounting car; which may be still further ameliorated by the setting of said journal bearings of the 85 bell-crank levers nearer midway between said wheel axle bearings. The perforate car attachment ends 13 of said bell-crank levers, are secured to the car sills 14, by the screw-tipped attachment ends of the guide bolts 15, 90 which bolts are loosely seated in the perforate attachment ends 13 of the bell-crank levers, through the perforate rubber spring cushion blocks 16 and the washers 17, where they are securely fastened by the screw nuts 18. The 95 upper ends of said guide bolts pass through one of the perforate ends of the upper ball housing plates 19, and through their bolt holes 20, in said truck or car sills 14, and their upper screw tips are there secured by the 100 screw nuts 21, which tightly draw the swell shoulder bars or nuts 22 that integrally project from said guide bolts against said upper ball housing plates 19. The reverse perforate

end of said plates are secured to said sills by the bolts 23 that pass through said sills, and said plates and their screw tips are secured by the screw nuts 24. 25 represent the lower ball bearer seats that surmount the terminal ends of said bell-crank levers. 27 are cup ball housings that are bedded in said seats in which the bearer balls 28 are housed and work, correspondingly in their movements in 10 their cup housings 29 in the upper ball housing plates 19. As said bell-crank lever rises and falls, the said bearer balls 28 work within their housing cups and steady the movement of said bell-crank levers, in corrective response to the concussion of the wheels in their 15 passage over slight obstructions or inequalities on the tracks, said vertical movement of the long, nearly horizontal arms 30 of said bell-crank levers, on their guide bolts 15, being re-adjusted by said perforate rubber spring blocks 16 to bring said arms of the bell-crank lever back to their normal position. 20 31 represents the short nearly vertical arms of the bell-crank levers, the lower ends of which are connected to spring valve reels 32, that run within the aforesaid tubular bases 6 of the compound pedestal angle frames 7. 33 are spiral springs that lie and work horizontally within said tube bases between the 25 outer ends of said reels and the disk stopper ends 34 of said tube bases. 35 represents volute springs that lie and work within said tubular bases 6 between the inner ends of said reels 32 and the adjacent ends of the 30 tubular tension beams 36.

The said tubular tie beams constitute another element of the invention. Their respective tension ends 37 are inserted by machine pressure within the corresponding tube 35 holder ends 38 of the respectively projecting ends of the aforesaid tube bases 6 of the compound pedestal 7. The said tubular tie beams have integral disk closures 39 at their ends, which greatly strengthen said ends of the tie 40 tubes to resist fracture when being inserted by extreme machine pressure within said tube holder ends 38 of said tube bases 6 of the compound pedestal frames, so as to maintain a reliable tension hold, without being 45 pierced by bolt holes and tie bolts that constitute points of weakness, and starting points for fracture under adverse strains on said tubular ties. It is therefore claimed that said tubular tension ties 36, within their tubular 50 tension holds 38, which holds are reinforced by the peripheral beading 38', add greatly to the strength and to the stiffness of the combination and its tie, with the same amount of metal as used in the usual solid tie beams, 55 but more advantageously disposed to brace itself and to brace its tie connection.

40 represents cross spring bearer bars that integrally connect the respective sides of the compound pedestal frames at their outer ends 60 at somewhat lower levels than that reached by the lowest dip of the long arm 30 of the bell-crank lever, and 41 are the rubber or

other suitable spring cushions that are seated on said cross connecting bars, and in cases of extreme concussions said spring cushions arrest the too extreme depression of the long arms 30 of the bell-crank lever, under the weight of the loaded truck or car. 70

42 represents the lower and 42' the upper clutches of the grip holder clamps that embrace around said tubular tie beams 36. 75

43 are the base bars and 44 the surmounting bars of the angle motor carrier frame 49, the conjoint double perforate ends 45 of which bars are secured by the screw bolts 46 and 80 nuts 47 to the perforate duplicate flanges 48 on each side of said grip holders through which they pass.

50 represents wing flanges that surmount the grip holders 42 and 42', and which wings 85 have raised square edged shoulder blades 51 that firmly brace against the upper bars 44 of said motor carrier frame 49. 54 are the central vertical tie bolts which are seated in the perforate centers 55 of said respective 90 base and upper bars of the motor carrier frame 44 and are there secured by the screw nuts 56.

57 represents the life guards that are secured together at their angle fronts by rivets 58 to the perforate overlap tie plate 59 and at 95 their rear ends are secured by rivets 60 to the perforate angle bent attachment bars 61, that are themselves secured by rivets or bolts 62 to the curved end bars 63 of the running gear frame. 100

64 represents upper tie bars the screw attachment ends 65 of which pass through the perforate corresponding bail shaped coupling inner ends 66 at the upper angle corners of the compound pedestal frames 7, where said tie bars are stayed by the shoulder nuts 67 and are secured in their seats by the screw nuts 68.

The general combination and functions of the invention have been nearly sufficiently described during the introductory description of its several parts, but it may be further stated that by means of the laterally diverted bearings of the journal bolts 12 of the supporting bell-crank levers toward the midway centers in the running gears from that of the axle bearings to any desired proportionate distance from said axle bearings, (it being shown see Fig. III located at about one fourth of the distance,) just in the same relative proportion will the elevation of said bearings of said bell-crank lever be reduced as compared to that of the axle and wheel, when the latter runs over any impediment on the track; but I do not confine myself to said gain of one fourth as it affects concussion in the respective positions of the axle and supporting bell-crank lever bearings, for it is evident that the bearings of said bell-crank lever for either passenger cars or trucks that carry easily destructible freight may be placed as near as desired to the common center of the running gears, and to the same relative degree still further reduce the con- 110 115 120 125 130

cussion; also the horizontal springs 33 and 35 in their elastic influence on the bell-crank lever very materially ameliorates the concussion.

5 I claim as my invention—

1. In an anti-concussion lateral spring journal bearing for car trucks, the combination of the wheels 2, the axles 3, the spring bearer boxes 4, the bell-crank levers 11, and the journal bolts 12 forming bearings for the said bell-crank lever and located between the front and rear axle bearings; substantially as shown and described.

15 2. In an anti-concussion lateral spring journal bearing for car trucks the combination of the axles 3 provided with their direct bearings, and the bell-crank levers 11, that support the car, the lateral spring connections of said levers with said axle bearings, and the 20 journal bolt bearings of said bell-crank levers at points intermediate between the front and rear axle bearings, arranged to reduce the concussion on the cars or trucks from the movement of the wheels, substantially as 25 shown and described.

3. In an anti-concussion lateral spring journal bearing for car trucks, the combination of the axle journals provided with their direct bearings, the bell-crank levers 11, the journal bolts 12, located between the direct bearings of the axles, the truck or car sills 14, the upper ball housing seats 19, the lower ball housing seats 25, the bearer balls 28, the attachment bolts 23, and the guide traveler bolts 35 15; substantially as shown and described.

4. In an anti-concussion lateral spring journal bearing for car trucks, the combination of the axle journals, the wheels, the direct journal boxes of said axles, the bell-crank levers 40 11, the journal bolts 12 on which said levers are mounted said journal bolts provided with bearings 9 midway between the direct forward and rear bearings of the axles, the upper ball housing plates 19, provided with the cup 45 29, the lower ball housing seats 25 provided with the cup housings 27, the bearer balls that work in said housings, the truck or car sills 14, the guide bolts 15, fast seated in said sills, said bell-crank levers provided with loose bearings, in which the pendant ends of said bolts 15 work, the perforate rubber cushion blocks 16, the washers beneath said cushions through which cushions and washers said bolts pass and the screw 55 18 secured to said bolts; substantially as shown and described.

5. In an anti-concussion lateral spring journal bearing for car trucks, the combination of the compound pedestal frames 7, having the 60 12 tubular bases 6 and the tube holder ends 38, the circular bosses 8 and 8' and inner guide lugs 8², the truck wheels, the axles on which said wheels are fast mounted, the spring bearer boxes in line with said axles, the bell-crank levers 11, the journal bolts 12 on which 65 said levers work, said bolts having bearings

midway between the axle bearings, the tubular tension tie beams 36, the tension ends of said tie beams fast tension held within said tube holder ends 38 of said compound pedestal frames, the car truck sill, the connection of the long arms of said bell-crank levers to said sill, the spring valve reels pendent from short arms of bell-crank lever, the horizontal spiral springs 33 that work at one end of said reel and the volute spring 35 that works between the other end of said reel and the enclosed tension end 37 of the tie tube 36; substantially as shown and described.

70 6. In an anti-concussion lateral spring journal bearing for car trucks, the combination of the compound pedestal frames 7, having the perforate connecting bail shaped ends 66, the bell-crank levers 11, having the long arms 30, provided with the perforate attachment ends 13, the short pendent arms 31, and the elbows 10 between said arms, said elbows provided with the journal bearings 9, the upper tie beams 64 secured to said ends 66 of said pedestal frames, the journal bolts 12, the truck 80 or car sills 14, carried by said bell-crank levers, the horizontal springs 33 and 35, the tubular tension tie beams 36 having the integral disk closures 39, the ball housing seats 19 and 25, provided with the cup housings 27 85 and 29, the bearer balls 28 that work in said housings, the sliding attachment bolts 13, and the perforate spring blocks 16; substantially as shown and described.

90 7. In an anti-concussion lateral spring journal bearing for car trucks, the combination of the compound pedestal frames 7, having the tubular bases 6, the tubular tension tie beams 36, the corresponding tube holder ends 38, the upper tie bars 64 with the screw attachment 100 ends 65 and coupling ends 67, the bell-crank car bearer lever 11, the journal bolts 12, the horizontal lateral play springs 33 and 35, the cross spring bearer bars 40, the spring cushions 41 and the life guards 57, the grip holder clamps 42 and 42', and the motor carrier frame 49 having the base bars 43 and the surmounting bars 44; substantially as shown and described.

105 8. In an anti-concussion lateral spring journal bearing for car trucks, the combination of the compound pedestal frames 7, the tubular tension tie-beams 36, the corresponding tube holder ends 38 having the peripheral reinforce beading 38', the upper tie bars 64, coupled to said pedestal frames, the bell crank car bearer levers 11, the motor carrier frame 49 having the base bars 43 and surmounting bars 44, the grip holder clamps that secure 110 said frames to said tie beams 36, and the wing flanges 50 that project from the holder clamps, said flanges provided with the brace shoulders 51; substantially as shown and described.

115 WILLIAM SUTTON.
